UNITED STATES PATENT OFFICE.

CHARLES ALGERNON PARSONS, OF NEWCASTLE UPON TYNE, ENGLAND.

DEVICE FOR PURIFYING STEAM.

1,247,320.

Specification of Letters Patent.

Patented Nov. 20, 1917.

Application filed February 3, 1914. Serial No. 816,267.

To all whom it may concern:

Be it known that I, CHARLES ALGERNON PARSONS, a subject of the King of Great Britain and Ireland, residing at Heaton Works, Newcastle-upon-Tyne, in the county of Northumberland, England, have invented certain new and useful Improvements in Devices for Purifying Steam, of which the following is a specification.

10 This invention relates to improvements in the utilization of steam in turbines and other engines.

It is well known that steam has a corrosive action upon the casings, rotors and blades of steam turbines especially in the case of marine installations. It is found that such corrosive action is almost entirely due to salt principally in the form of chlorides of sodium and magnesium coming over with 20 the steam from the boilers as sometimes happens when salt is allowed to get into the boilers through leaky condensers or in some other way. The corrosion arises from a chemical action on the part of the salts between the steel or cast iron of the bodies of 25 the rotor or casing respectively, and the brass or copper of the working blades and dummy strips.

It is also found that this corrosion is practically limited, at any rate to any serious extent to the first few rows of blades and dummy strips with which the fresh steam comes into contact.

The object of the present invention is to 35 enable this corrosive action to be avoided.

The invention consists in a strainer through which the steam passes before entering the turbine or other engine, the steam in passing through said strainer coming into 40 contact with metals similar to or not less active than those of the turbine or engine parts so that the corrosive action of the steam is expended in the strainer.

The invention further consists in the improved strainer hereinafter indicated.

Figure 1 is a sectional front elevation through a strainer according to the present invention.

Fig. 2 is a sectional side elevation at right angles to Fig. 1.

Fig. 3 is a sectional plan on the line A—A of Fig. 1.

Fig. 4 is a view of one of the plates *c* seen from below.

Fig. 5 is an enlarged sectional view of 55 one of the groups of perforated plates and baffles.

Fig. 6 is a plan of Fig. 5. In carrying this invention into effect in one manner, the strainer *a* is as usual placed 60 in the conduit by which the steam is conveyed to the turbine and consists in a number of compartments *b* through which the steam passes in parallel. The steam enters at *g* and leaves at *h* following the course indicated by the arrows, the compartments being provided with apertures *j* for passage of the steam. In each compartment are provided perforated partitions *c* upon which are mounted alternate plates of brass *d* and 65 steel, *e*, these plates being perforated. The effective area of these perforated plates is controlled by one or more baffles *f*. A removable cover *g* is provided at the side of the strainer *a*.

It will be seen therefore that the steam in passing through each compartment of the strainer comes into contact with alternate plates made of the same metals as the parts of the turbine. The corrosive action of the 70 steam on these metals therefore takes place in the strainer and the salts in the steam producing the corrosion are killed before they reach the parts of the turbine. In this way the steam is rendered chemically inactive 75 upon the parts of the turbine before it is admitted thereto.

The action which takes place within the device appears to be principally a chemical one, the iron plates being attacked by the 80 salts present in the steam, principally the sodium chloride, and by hydrochloric acid, which latter is the result of chemical action between the steam and the magnesium chloride.

It is preferable that the steam should pass through the perforated plates of brass and steel *d* and *e* in the strainer at a comparatively high velocity and that the area through the perforation of these plates be 85 made small enough to insure a small pressure drop for instance of 3 to 5 lbs. per square inch between the pressure of the steam at the inlet to and the outlet from the strainer. It is found that the extraction 90 of a certain amount of the intrinsic energy from the steam in this manner promotes the chemical action of the steam upon the per-

forated brass and steel plates *d* and *e* and insures the effectiveness of the strainer in rendering the steam chemically inactive.

The mechanical construction of the strainer is such that the perforated brass and steel plates can be readily removed and replaced.

It will be seen therefore that by this invention the detrimental corrosive action of the steam upon the metal of which the turbine parts are formed is transferred from the turbine parts themselves to a strainer where the products of the corrosion can be easily removed and the parts attacked readily renewed as often as required.

The actual construction of a strainer for the purpose of this invention it will be seen can be considerably modified without involving departure from the spirit of the same.

Having now particularly described and ascertained the nature of my invention and in what manner the same is to be performed I declare that what I claim is:

1. A device for rendering steam chemically inactive, comprising in combination, a casing, a steam inlet and a steam outlet to said casing, a plurality of compartments in said casing, inlet and outlet apertures to each of said compartments, all said inlet apertures communicating by a common inlet passage with said casing inlet, and all said outlet passages communicating by a common outlet passage with said casing outlet, a group of perforated plates between the inlet and outlet of each of said compartments, said plates being alternately of different metals, the relation between the area for parallel flow through all said groups and the area of the inlet to said casing being such as to cause a high velocity of steam flow through said perforated plates.

2. A device for rendering steam chemically inactive comprising in combination, a casing, a steam inlet and a steam outlet to said casing, a plurality of perforated plates between said inlet and said outlet, through which the steam is caused to pass said plates being alternately of different metals, and means associated with said plates to cause the steam to traverse the perforations at high velocity.

3. A device for rendering steam chemically inactive, before admission to a turbine having blades composed of metals different from the blade supporting means, comprising in combination, a casing, a steam inlet and a steam outlet to said casing, a plurality of perforated plates within said casing, and interposed between said inlet and said outlet, said plates being alternately of a metal similar to the blade metal and a metal similar to the blade supporting metal, and means to cause said steam to traverse said perforations at high velocity.

In testimony whereof I affix my signature in presence of two witnesses.

CHARLES ALGERNON PARSONS.
